INK FOUNTAIN FOR USE IN PRINTING MACHINES

William F. Huck, Richmond Hill, N. Y., assignor to R. Hoe & Co., Inc., New York, N. Y., a corporation of New York

Application December 30, 1937, Serial No. 182,596

6 Claims. (Cl. 101—365)

This invention relates to fountains or reservoirs, and more particularly to undershot ink fountains for use in printing machines.

An object of this invention is the provision of improved means and method for adjusting the inclined bottom plate or scraper blade of the fountain relative to the peripheral surface of the fountain roller to thereby accurately control the quantity of ink supplied from the fountain.

A specific object of this invention is the provision of improved mechanism for adjusting the fountain scraper blade relative to the peripheral surface of the fountain roller, the adjusting mechanism including a screw which is movable linearly in directions towards and away from the blade by its rotary movement, and the screw operably engages an adjusting member to impart linear movement to the adjusting member in directions towards and away from the blade in directions opposed to the linear movement of the screw, and the amplitude of linear movement of the adjusting member being less than the first member thereby imparting accurately controlled adjusting movement to the blade relative to the peripheral surface of the fountain roller.

A further object of this invention is to provide an undershot ink fountain which includes a flexible bottom plate or scraper blade which cooperates with the peripheral surface of the fountain roller to control the quantity of ink supplied from the fountain, and means for adjusting the lower terminal of the scraper blade relative to the peripheral surface of the fountain roller, which means include a screw having a portion threadedly secured to a fixed member and a block threadedly secured to a separate threaded portion of the screw and engaging the fountain blade, said block being movable linearly towards and away from the blade by rotary movement of the screw thereby accurately adjusting the terminal of the fountain blade relative to the peripheral surface of the fountain roller.

Another object of this invention is to provide an undershot ink fountain for use in printing machines, the fountain having a flexible inclined bottom plate or scraper blade mounted for co-operable engagement with the peripheral surface of the fountain roller to control the quantity of ink supplied from the fountain, a plurality of manually adjustable screws having portions threadedly secured to a fixed member, a nut threadedly secured to another threaded portion of each screw, means for holding the nuts against rotation so that rotary motion of each screw moves it linearly towards and away from the

blade and also rotates the screw relative to its nut thereby moving the nut linearly towards and away from the blade, the linear movement of each nut being in directions opposed to the linear movement of the screw and of less amplitude thereby imparting accurately controlled adjusting movement to the flexible fountain blade relative to the peripheral surface of the fountain roller.

A more specific object of this invention is to provide an undershot ink fountain for use in printing machines, the fountain having a flexible inclined bottom plate or scraper blade mounted for co-operable engagement with the peripheral surface of the fountain roller to control the quantity of ink supplied from the fountain, a plurality of manually rotatable adjusting screws, each screw having threads of given pitch threadedly engaging a fixed member and separate threads of different pitch, a block threadedly secured to the said separate threads, means for holding the block against rotation so that rotary movement of the screw moves it linearly in directions towards and away from the blade and also rotates the screw relative to its block thereby moving the block linearly towards and away from the blade, the rotative movement of the screw of given amplitude imparts linear movement to the adjusting block of amplitude determined by the difference of pitch of the threads of the screw.

Another object of this invention is to provide an undershot ink fountain for use in printing machines, the fountain including a fountain roller, an ink roller, a ductor roller, arms supporting the ductor roller for operable movement between the fountain roller and the ink roller, an improved means for rotatably securing the ductor roller to the said arms.

It is also an object of this invention to provide an ink fountain of generally improved construction, whereby the device will be simple, durable and inexpensive in construction as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion, and minor details of construction may be made within the scope of the claims without departing from the spirit or sacrificing any advantages of the invention.

For a complete disclosure of this invention, a detailed description of the improved ink fountain for use in printing machines will now be given in connection with the accompanying drawings forming a part of the specification, wherein:

Figure 1 is a side elevation of the improved fountain depicting the improved fountain blade adjusting means and the cooperating ductor mechanism and improved ductor roller sockets,

Figure 2 is an elevational view of Figure 1 looking in the direction of the arrow depicted in Figure 1, and

Figure 3 is a vertical transverse sectional view taken on the line 3—3 of Figure 2 and looking in the direction indicated by the arrows.

Referring to the drawings in which similar reference characters designate corresponding parts, there is shown an undershot ink fountain having a rigid inclined body portion or base 10 and spaced side walls or cheeks 11 which extend upward from the base 10. A fountain roller 12 is provided, and the opposed terminals of the fountain roller shaft 13 are mounted in suitable antifriction bearings 15 supported by brackets 16 secured to the opposed sides of the fountain body or base 10 by screws or other suitable securing devices 17, as best seen in Figures 1 and 2 of the drawings. In these figures only one side of the machine is depicted, but inasmuch as the supporting mechanism is duplicated at each side of the machine, it is of course, understood that similar brackets and bearings are provided at the opposed side of the machine. A suitable plate or cap 18 is secured to each bracket 16 to complete the closure of the antifriction bearings 15. A pad or securing lug 19 is carried by the fountain base 10 and it is provided with apertures for the reception of suitable securing devices to secure the fountain to the printing machine frame in conformity with the usual practice. Inasmuch as this mode of securing fountain structures to printing machine frames is well known and understood by those skilled in the art, the machine frame and the securing elements are not depicted in these drawings.

The upper surface of the inclined base 10 is preferably machined or finished to slidably support a blade support or carriage 20, and a flexible plate or scraper blade 21 is secured to the upper surface of the inclined blade support or carriage 20 by rivets or other suitable securing devices 22, as best seen in Figures 2 and 3 of the drawings. The lower terminal of the flexible scraper blade 21 extends beyond the lower terminal of the blade support 20 to permit flexing movement of this portion of the plate or blade towards and away from the peripheral surface of the fountain roller 12. As will be hereinafter explained, the lower flexible terminal of the scraper blade 21 operably engages the peripheral surface of the fountain roller 12, thus subjecting the engaged edge of the blade to wear. In order to adjust the blade 21 for linear movement to and from the fountain roller 12 to compensate for this wear a flange or ear 23 extends downwardly from the outer terminal of the scraper blade carriage 20. Apertures 25 extend through the flange or ear 23 and a screw 26 is swiveled in each aperture, and the inner terminal of each screw 26 threadedly engages one of the threaded apertures 27 formed in the outer terminal of the base 10. Other screws 26' are screw threaded into the flange 23 and extend therethrough and abut the edge of the fountain base 10 and these screws are

provided with lock nuts 26''. The screws 26 function to draw the carriage 20 and blade 21 away from the fountain roller 12, and the screws 26' function to force the carriage 20 and blade 21 towards the fountain roller, consequently, means are thus provided for adjusting the blade support or carriage 20 and the scraper blade 21 towards or away from the fountain roller in order that the inner terminal of the flexible blade 21 may be positioned in accurate cooperable position in relation to the peripheral surface of the fountain roller. After the blade 21 has been adjusted in proper operative relation to the peripheral surface of the fountain roller 12, the blade carriage 20 is immovably secured to the fountain base 10 by screws 24 which threadedly engage apertures formed in the fountain blade carriage 20, and these screws 24 are received within elongated slots 14 formed in the fountain base 10 to permit adjusting movement of the plate carriage 20 relative to the base 10.

In order to accurately feed or supply the requisite quantity of ink from the fountain bowl 30 defined by the end walls or cheeks 11, peripheral surface of the fountain roller 12 and the bottom plate or scraper blade 21, it is necessary that the lower terminal of the flexible scraper plate 21 be adjusted with extreme accuracy relative to the peripheral surface of the fountain roller 12. Heretofore attempts have been made to adjust the scraper blade relative to the peripheral surface of the fountain roller by adjusting screws, but such arrangements have proven unsatisfactory, because, even though very fine threads are employed on the adjusting screw, a very limited rotative movement of the adjusting screw imparts excessive adjusting movement to the blade, thereby making it very difficult to properly adjust the blade terminal relative to the peripheral surface of the cylinder.

A feature of applicant's invention resides in the novel means and method of adjusting the scraper blade 21 relative to the peripheral surface of the fountain roller 12, and this adjusting mechanism includes a plurality of operating members or thumb screws 31 threadedly secured in threaded apertures formed in a thickened portion 32 of the fountain base 10, and each screw is provided with a manipulating head or wing 33. The inner or upper terminal of each adjusting screw 31 is reduced, and provided with threads 35 which threadedly engage a threaded aperture 36 formed in a rectangular adjusting block or nut 37 which is mounted for axial or linear movement in a recess 38 formed in the fountain base 10. The recess 38 extends transversely across the fountain, and at the lower or inner terminal of the recess a transversely extending bar or guide member 39 is positioned. The bar 39 is secured to the fountain base 10 by machine screws or other suitable securing devices 40, and it is so positioned that a face thereof engages a face of each adjusting block or nut 37 to prevent rotative movement of the block but permits free axial sliding movement thereof. The threads 35 formed on the reduced portion of each screw 31 are preferably of somewhat finer pitch than the threads formed on the body of the screw, so that as the screw 31 is rotated through a determined angle, the screw 31 moves axially or linearly in directions towards or away from the scraper blade 21 a definite distance in accordance with the pitch of the threads on the body of the screw 31. Inasmuch as the threads 35 formed on the reduced portion of the screw 31

are of slightly finer or different pitch than the threads formed on the main body of the screw 31, it is manifest that as the screw is rotated the nut 37 will move axially in directions towards or away from the fountain roller 12 a distance less than the axial movement of the screw 31 for the same degree of rotative movement. Consequently, by suitably selecting the pitch of the threads formed on the body of the screw 31 and the threads 35 formed on the reduced portion or inner terminal of the screw, the differential action produced due to the different pitch of the different threads permits the nut to move axially any desired distance with a given degree of rotatory movement of the screw 31. Thus it is seen, by this arrangement relatively great rotative movement may be imparted to the screw 31, and the pitch of the threads can be so chosen that this movement will impart only infinitesimal axial movement to the nut. Consequently, the operator, owing to the fact that relatively great angular rotative movement of the screw 31 results in very small axial movement of the nut 37, has complete control of the adjusting mechanism to permit him to accurately adjust the inner terminal of the scraper blade relative to the peripheral surface of the fountain roller to thus accurately control the quantity of ink supplied from the fountain past the blade terminal to any suitable inking mechanism.

As shown in Figure 2, a plurality of the nuts 37 and screws 31 are provided, and these nuts are positioned end to end transversely across the fountain thereby permitting the operator to adjust any chosen transversely disposed portion of the blade relative to the peripheral surface of the fountain roller, thus giving to the operator accurate control of the supply of ink throughout the length of the fountain.

The fountain may supply ink to any selected inking mechanism, and, as depicted in Figure 1, the first roller 41 of a suitable inking mechanism is rotatably mounted adjacent the fountain roller 12. The inner terminal of an arm 42 is rigidly secured at each side of the fountain to a shaft 43, as shown in Figure 1, and the shaft 43 is mounted for rocking movement in conventional bearings, not shown. A lever 44 extends downwardly from an arm, and the lower terminal of the lever 44 is pivotally secured to a link 45, as indicated at 46. The opposed terminal of the link 45 extends through an aperture 47 formed in a stud 48 or any other suitable component of the printing machine, thus permitting the link 45 to slide within the aperture 47. A shoulder 50 is formed adjacent one terminal of the link 45, and this shoulder is engaged by a suitable washer 51. A similar washer 52 engages the stud or member 48, and a helical spring 53 surrounds the link 45 and is positioned between the spaced washers 51 and 52 to normally bias the arm 42 for clockwise movement. The upper terminal of each arm 42 is provided with a semi-cylindrical surface 56, as best seen in Figure 1 of the drawings. An arcuate cap 57 is provided with a similar arcuate surface 58, and the cap 57 and upper terminal of the arm 42 provide a bearing socket to rotatably receive the shaft 60 of a ductor roller 61. The arcuate surfaces 56 and 58 may engage the shaft 60 to provide bearing surfaces therefor, or these arcuate surfaces may engage antifriction bearing members carried by the shaft 60 to thus rotatably support the shaft 60 and roller 61. Both arrangements are well understood by those skilled in the art, therefore, it is thought that

the arrangement depicted in Figure 1 amply illustrates this phase of applicant's invention. Each arm 42 has the lower terminal of a link 62 pivotally secured thereto, as indicated at 63, and the upper terminal of each link 62 is pivotally secured to a cap 57, as indicated at 65. A securing yoke or member 68 is pivotally secured to each arm 42, as indicated at 67, and a screw 66 is threadedly received therein and the inner terminal of the screw abuts a surface 70 of the cap 57 to thereby lock the cap 57 to the bearing portion of the arm 42.

While only one ductor roller bearing socket has been depicted in the drawings, it is of course to be understood that a similar socket is provided at the opposed side of the machine, and, inasmuch as the construction and operation of both sockets are identical, it is thought that the present illustration is ample for the disclosure of this invention. By securing each cap 57 to the upper portion of its supporting arm 42 through an interposed link 62, flexibility is provided which enables the securing member or yoke 68 to be readily secured in position to lock the cap 57 in operative position upon the fixed portion of the socket, and, furthermore, this flexibility also permits the arcuate bearing surface or bearing supporting surface 58 of the cap 57 to accurately align with the cooperating arcuate surface 56 of the arm 42 to present true concentric bearing surfaces or bearing supporting surfaces for the reception of the ductor roller shaft 60 or antifriction bearing member for the shaft, even though the apertures for the pivotal connections 62 and 63 are not accurately located relative to 35 the arcuate surfaces 56 and 58.

In order to operably move the ductor roller 61 between the fountain roller 12 and the roller 41 of the inking mechanism, in conformity with the usual practice, a link 72 is pivotally secured to an ear 73 extending upwardly from an arm 42, as indicated at 74. The opposed terminal of the link 72 is connected to any suitable cam operated mechanism forming a part of the printing machine, and, inasmuch as such actuated mechanism is well understood by those skilled in the art and forms no part of this invention, it has not been here illustrated.

In operation, the link 72 is moved back and forth by the cam operated mechanism of the printing machine and during this operation the spring 63 stresses the ductor roller 61 towards the fountain roller 12. As the link 72 moves outwardly the arms 42 and shaft 43 move about their pivot against the tension of the springs 53 and thereby move the ductor roller into engagement with the roller 41 of the inking mechanism. As this operation is completed ink is conveyed from the fountain roller 12 by the ductor roller 61 to the inking mechanism roller 41, in conformity with the usual practice.

The quantity of ink supplied from the fountain bowl or reservoir 30 to the ductor roller 61 is of course determined by the degree of adjustment imparted to the lower flexible portion of 65 the scraper blade 21, and, as explained hereinbefore, relatively great rotatory movement of each adjusting screw 31 imparts relatively small axial or linear movement to the lower terminal of the scraper blade through the operably interposed 70 adjusting nut 37. Inasmuch as a plurality of nuts 37 are positioned end to end entirely across the fountain bowl throughout the axial length of the operative portion of the fountain roller 12, and since each adjusting screw 31 permits the 75

operator to impart infinitesimal adjusting movement to the engaged or selected portion of the fountain blade, it is manifest that this mechanism affords the operator complete and accurate control over the quantity of ink supplied from the fountain throughout the length of the fountain roller.

Having thus described my invention, what I claim as new and useful is:

- 10 1. In an ink fountain, a reservoir, a fountain roller, a blade having an edge cooperable with the roller to control the quantity of ink supplied from the reservoir, an adjusting member mounted for linear movement in directions to and from the blade and operable to adjustably move the blade relative to the fountain roller by its said linear movement, a fixed member, a screw having threads of given pitch threadedly engaging said fixed member and separate threads of different pitch directly and threadedly engaging the linearly movable adjusting member so that rotary movement of the said screw of given amplitude imparts linear movement to the adjusting member of amplitude determined by the difference of pitch of the said different threads of the screw.
- 15 2. In an ink fountain, a reservoir, a fountain roller, a blade having an edge cooperable with the roller to control the quantity of ink supplied from the reservoir, a plurality of adjusting members mounted for linear movement in directions to and from the blade and each adjusting member being operable to adjustably move the blade relative to the roller by the linear movement of the adjusting member, means engaging the adjusting members to hold them against rotation, a fixed member, a screw having threads of given pitch threadedly engaging said fixed member and separate threads of different pitch directly and threadedly engaging each linear movable adjusting member so that rotary movement of the screw of given amplitude imparts linear movement to the adjusting member of amplitude determined by the difference of pitch of the different threads of the screw.
- 20 3. In an ink fountain, a reservoir, a fountain roller, a flexible blade having an edge cooperable with the roller to control the quantity of ink supplied from the reservoir, an adjusting block having a threaded aperture formed therein and mounted for linear movement in directions to and from the blade and engaging the blade to adjustably move it relative to the fountain roller by the linear movement of the block, a fixed member, a screw having threads of given pitch threadedly engaging the fixed member and separate threads of different pitch threadedly engaging the threaded aperture formed in the block so that rotary movement of the screw of given amplitude imparts linear movement to the adjusting block axially relative to the screw of amplitude determined by the difference of pitch of the different threads of the screw.

4. In an ink fountain, a reservoir, a fountain roller, a flexible blade having an edge cooperable with the roller to control the quantity of ink supplied from the reservoir, a plurality of adjusting blocks engaging the blade and positioned end to end across the fountain, each block having a threaded aperture formed therein, a bar engaging the blocks to hold them against turning movement and to permit linear movement of the blocks in directions to and from the blade, a fixed member, a screw for each block having threads of given pitch threadedly engaging the fixed member and separate threads of different pitch threadedly engaging the threaded aperture of each adjusting block so that rotary movement of given amplitude of each screw imparts linear movement to its adjusting block axially relative to the screw of amplitude determined by the difference of pitch of the different threads of the screw.

5. In an ink fountain, a reservoir, a fountain roller, a flexible slidably-mounted blade having an edge cooperable with the roller to control the quantity of ink supplied from the reservoir, an adjusting member mounted for linear movement in directions to and from the blade and operably connected with the blade to adjustably move the blade relative to the fountain roller by the linear movement of the adjusting member, a fixed member, a screw having threads of given pitch threadedly engaging the fixed member and separate threads of different pitch directly and threadedly engaging the adjusting member so that rotary movement of given amplitude of the screw imparts linear movement to the adjusting member of amplitude determined by the difference of pitch of the different threads of the screw.

6. In an ink fountain, a reservoir, a fountain roller, a blade cooperable with the roller to control the supply of ink from the reservoir, an adjusting member operably supported by the fountain and cooperable with the blade and mounted for linear movement substantially perpendicular to the blade and operable to adjustably move the blade relative to the fountain roller by its linear movement, and an operating member mounted for rotary and linear movement relative to the said adjusting member and operably connected therewith to move the adjusting member bodily relative to the operating member by the movement of the operating member, the operable connection between the adjusting member and operating member causing the amplitude of movement of the adjusting member relative to the operating member to be less than the corresponding movement of the operating member to thereby impart adjusting movement to the adjusting member and blade in the direction of movement of the operating member of less amplitude than the corresponding movement of the operating member.

WILLIAM F. HUCK.
